US0D1057026S

(12) **United States Design Patent** (10) **Patent No.:** **US D1,057,026 S**
(45) **Date of Patent:** **** Jan. 7, 2025**

(54) **GAMING MACHINE**

(71) Applicant: **AGS LLC**, Las Vegas, NV (US)

(72) Inventors: **Sigmund Hyunjai Lee**, Atlanta, GA (US); **Ryan Patrick Rye**, Suwanee, GA (US); **Rachel Calhoun Lewis**, Atlanta, GA (US); **Daniel Kendall Harden**, Palo Alto, CA (US); **Benjamin Martin**, South San Francisco, CA (US)

(73) Assignee: **AGS LLC**, Las Vegas, NV (US)

(**) Term: **15 Years**

(21) Appl. No.: **29/823,659**

(22) Filed: **Jan. 19, 2022**

Related U.S. Application Data

(62) Division of application No. 29/700,522, filed on Aug. 2, 2019, now Pat. No. Des. 969,927.

(51) **LOC (15) Cl.** **21-01**

(57) **CLAIM**

The ornamental design for a gaming machine as shown and described.

DESCRIPTION

FIG. 1 is a front perspective view of a gaming machine of the present disclosure.

FIG. 2 is a front elevation view thereof.

FIG. 3 is a rear elevation view thereof.

FIG. 4 is a first side view thereof.

FIG. 5 is a second side view thereof; and,

FIG. 6 is a top plan view thereof.

The shade lines in the Figures show contour and not surface ornamentation. The broken lines in the Figures show portions of the support structure and its surrounding environment that form no part of the claimed design.

1 Claim, 6 Drawing Sheets
